MARCUS H. RHODES, OF NEW HAVEN, CONNECTICUT, ASSIGNOR TO M. H. RHODES, INC., OF WILMINGTON, DELAWARE, A CORPORATION OF DELAWARE

SWITCH

Application filed November 21, 1929. Serial No. 408,807.

This invention relates to electric switches, and with regard to certain more specific features, to timed, delayed action switches. Among the several objects of the invention may be noted the provision of an electric switch having improved means for effecting a higher speed of circuit making and breaking; the provision of a switch having a delayed action subsequent to actuation thereof; the provision of a switch of the class described which may have the timed delay feature temporarily thrown out of operation to permit non-delay action; and the provision of a switch of the class described which shall be of maximum simplicity and ruggedness and which shall have improved wearing and operating qualities. Other objects will be in part obvious and in part pointed out hereinafter.

The invention accordingly comprises the elements and combination of elements, features of construction, and arrangements of parts, which will be exemplified in the structure hereinafter described, and the scope of the application of which will be indicated in the following claims.

In the accompanying drawings, in which are illustrated several of the various possible embodiments of the invention.

Fig. 1 is a plan view of a switch embodying the invention, the same being shown as set for time delayed, circuit breaking action;

Fig. 2 is a vertical, longitudinal section taken on line 2—2 of Fig. 1;

Fig. 3 is a vertical, longitudinal section taken on line 3—3 of Fig. 1;

Fig. 4 is a detailed plan view of a latch lever;

Fig. 5 is a developed view showing a gear train and connected parts, the development being defined and taken along line 5—5 of Fig. 2;

Fig. 6 is a view corresponding to Fig. 3, except that the parts are shown in their opposite extreme position;

Fig. 7 is a vertical section taken longitudinally of the switch on line 7—7 of Fig. 1, showing certain details;

Fig. 8 is a cross-section taken on line 8—8 of Fig. 7;

Fig. 9 is a cross-section taken on line 9—9 of Fig. 1, certain parts having been removed for purposes of clarity;

Figs. 10 and 11 are side elevations showing details of certain ratcheting elements of the invention; and,

Fig. 12 is a detailed side elevation showing an escapement and balance wheel.

Similar reference characters indicate corresponding parts throughout the several views of the drawings.

Referring now more particularly to Fig. 1, there is illustrated at numeral 10 a cover plate fastened down by two cover plate screws 53 to a lower U-shaped plate 1 (see Fig. 9 for the U-shape of plate 1). The cover plate 10 is provided with openings 56 and 57, the former for accommodating an oscillatory timing control handle or lever 8 and the latter for accommodating an oscillatory switching or circuit control lever 3, both levers extending outwardly through the openings 56, 57 from the inside of the switch. The function of the switching lever 3 is to make and break the circuit and also to be manipulated or actuated for varying the time of current flow after the switch lever 3 has been set to "off" position; and the purpose of the time lever 8 is to set the switch either for timed or non-timed operation. Next to the opening 56 is provided another opening 58 for displaying one portion of the periphery of a time indicator wheel 35, also located within the switch.

The cover plate screws 53 hold the cover 10 to said U-plate 1 (see Fig. 2) and U-plate screws 51 hold the said U-plate 1 to a porcelain box 25 (see Fig. 3). The box 25 forms an insulating housing for the switch parts. Pole pieces or line terminals 5 and 6 are supported therein, said pieces carrying contact screws 50 for fastening line wires or the like. Stationary knife blade extensions 59 and 60 depend from the poles 5 and 6 respectively for engagement by and with pairs of spring contactors or terminal engaging elements 11, said contactors 11 being formed with a connecting bar 61, the latter being pivoted on a pin 29. The pin 29 is fastened in the switch box.

It will be recognized that when the contactor 11, 61 is in the position shown in Fig. 3 that it is in circuit closing position with respect to the poles 5, 6. When the contactor is moved to the left (Fig. 6) the circuit is open, because the contactors 11 disengage from the blades 59, 60. In order to facilitate contacting, the extensions 59, 60 are somewhat sharpened as indicated at numeral 10 63 for ready engagement with flared ears 64 of the pairs of spring contactors 11. Operation of the contactors 11 is effected by forming an opening 65, in a block 24. The block 24 is fastened to the contactor part 11, 61. 15 Coordinating with and within this opening 65 is a depending tongue 66 of a switch hammer 4, said hammer 4 being adapted to swing on gudgeons 67. It will be noted that the switch hammer can swing freely through a 20 substantial arc before striking the sides of the opening 65, thus providing a lost-motion engagement. Inspection of Figs. 3 and 6 shows how the upper corners of the opening 65 are relieved, as indicated at numeral 62 25 for the purpose of permitting some continued movement of the switch hammer after it has opened and closed the switch. This function so places the switch hammer that the switch blade itself is locked in either its open or 30 closed position.

The switch hammer 4 is provided with a spring-seating extension 68 for receiving a switch spring 45, the spring being shown in Figs. 3, 6 and 9. The spring 45 extends upwardly and seats against the lower end 69 of a switch lever 3, the latter being swung on a switch lever pin 28 fastened between the sides of the U-plate 1. It will be seen thus far that the switch hammer 4, switch lever 3 and reacting switch spring 45 form an over-centering, toggle linkage. The action of this linkage is such that when the upper reaction point 93 of the spring at the end 69 crosses the center line CL of the switch hammer, for 45 instance, to the right, then the spring is put under compression and tends to throw the switch hammer to the left, provided there is no other mechanism to prevent it. For example, in Fig. 3 the spring is in compressed 50 reacting position for throwing the switch hammer sharply in a clockwise direction to the left, whereupon the tongue 66 will gain momentum in passing through its lost-motion path in the opening 65. Then the tongue 66 will strike the left hand end of the opening 65 with a sharp blow and instantly throw the contactors 11 out of engagement with the extension of the poles 5, 6. It should however, be noted that another part of the mechanism, which will be described, normally prevents this action from the Fig. 3 position until a predetermined release is effected. These 60 features will be described hereinafter.

Continuing the reference to the toggle action, it will be seen that if the switch lever

is thrown to its opposite, right hand extreme (Fig. 6), then the point 93 will pass over said center line CL. This passage over the center line throws the spring reaction into an over-centering relationship, such that the switch hammer is suddenly forced to assume a counter-clockwise movement. The tongue 66 travels with loss of motion in the reverse direction through the opening 65 and strikes the right hand thereof with a sudden blow, 70 thereby quickly snapping the switch shut, the contactors 11 moving to the right into engagement with extensions of the poles 5, 6. It is to be noted that when the switch lever 3 is thrown for closing the switch, that the 75 switch closes immediately, there being no delaying action in the mechanism such as will be explained in connection with opening the switch from the closed position.

As stated above, it will be noted that Fig. 3 80 shows the toggle linkage in such position that the spring is compressed and over-centered and ready to throw the switch hammer so as to open the switch, but there is a temporary mechanical restraint which will now 85 be described.

The parts above described are in one compartment of the box 25. This compartment is defined by the right side of the box (Fig. 9), part of the bottom thereof, and one side 90 70 of the U-plate 1 (see the right hand portion of Fig. 9). The other compartment is defined by the left wall of the box 25 (Fig. 9), the remainder of the bottom of the box. A flat plate 2, by means of plate spacers 26, is 95 100 spacedly mounted with respect to one wall 70 of the U-plate 1 (see Fig. 2 and Fig. 9). An arcuate opening 71 in the wall 70 of the U-plate 1 accommodates an extension ear 72 of the switch hammer 4. The function of 105 this extension is to be held and released for time delaying purposes. The coordinating latching apparatus therefor will be described hereinafter.

Pivoted to the switch lever 3 by means of an arm 37 is a pawl 7 which has an ear 73 provided for fastening a pawl spring 46, which spring reacts from the switch pin 28 to hold an oppositely extending ear 74 in engagement with the teeth of a ratchet wheel 18 located in said left hand compartment (see Figs. 7 and 9). The ear 74, which reaches through an opening 71-A in the plate 70, is pressed into engagement with the teeth of said ratchet 18 whenever the lever 3 is thrown into its "on" position and in the "off" position of the lever 3 said pawl ear 74 is drawn up against the side of the opening 71-A (as illustrated in Figs. 2 and 9) so as to permit clearing of the ratchet teeth by the ear 74 when it is desired to return the ratchet teeth according to the functions hereinafter set out. As will be made clear, the advance of the ratchet is one tooth every time the switch lever is thrown to "on" position. In 110 115 120 125 130

other words, when the lever 3 moves from "off" to "on" position, the pawl 74 rides down the left face of the opening 71—A, and engages a tooth such as X (Fig. 2) for advancement through an arc corresponding to the arc occupied by one ratchet tooth. The switch lever may be serially or repeatedly operated to advance the ratchet step by step.

The ratchet 18 (Figs. 7 and 9) is integrally movable with a main spring hub 30 and also with a main spring pawl wheel 13, so that the ratchet 18, hub 30 and main spring pawl 13 may turn together. On the other hand, there is provided a main gear wheel 19 which is relatively rotatable with respect to said parts 13, 18, 30.

A detail plan of the gear wheel 19 is shown in Fig. 11 and a detail plan of the main spring pawl 13 is shown in Fig. 10. The Figs. 10 and 11 show that the gear 19 is provided with openings 76 which are matched by detents 77 of pawl 13, a plurality of which detents are used. The detents 77 are formed in such a direction and engage said gear openings 76 in such a manner that when the operation of lever 3 results in movement of the ratchet 18, return of said ratchet under action of spring 44 is prevented by the engagement of the detents 77 with certain of the gear wheel openings 76. The gear wheel resists return action of the ratchet 18 caused by the initially provided tension in the main spring 44, because the gear train into which it is connected is at this time locked against movement.

The timing gear train referred to in the paragraph above is shown more particularly in Fig. 5 where in the gear 19 is shown as meshing with a pinion 21. Said pinion 21 is integrally rotatable with a gear 20 which meshes with a second pinion 32. A second gear wheel 20—A is integrally movable with the pinion 32 and meshes with a third pinion 33 the latter being made fast with a third gear wheel 20—B. This last wheel 20—B has its teeth so cut that it comprises an escape wheel which meshes with a slotted portion 22 of a balance staff. The staff 22 is integrally movable with balance wheel 14. Vibration of the balance wheel 14 is effected by means of a hair spring 80. A balance wheel stop pin 79 permits the escapement wheel 20—B to drive the balance wheel only a predetermined distance. The action (Fig. 12) is such that as the escapement wheel 20—B delivers energy to the balance staff 78 one tooth of the same fits into the groove 22 and revolves the balance staff 78. The hair spring 80 attached to the shaft is flexed by this rotation. At a predetermined point in the rotation of the staff 78 the said tooth of the wheel 20—B slips out of the slot 22. The hair spring 80 then reverses the rotation of the staff 78. Instantly the second or next tooth on the gear 20—B strikes against the smooth side of the

balance staff 78 and remains at a pressure position until the hair spring again rotates the balanced staff 78 back to a position where the second or next tooth is permitted to drop into the slot and ride by as the slot returns to repeat the cycle. It will be noted in this connection that this escapement has no pallet or anchor escapement means requiring complicated and delicate members.

It will be apparent from the above that the escapement will permit the gear train to run down under action of the main spring 44 only at a predetermined rate. It has also been made clear above that when the switch handle 3 is operated to its "on" position that the ratchet 18 is picked up by the pawl 74 to be moved through the angle subtended by one pawl tooth. This means that the main spring pawl 13 is moved the same angle and it is desirable at this time that the gear train be locked. In order to accomplish locking or braking there is held near the escapement a flexor 82 which is normally pressed into engagement with the staff 78. Thus the staff 78 is locked, this also locking the gear trains.

It is clear that under these conditions the ratchet 18 can be operated with the main spring pawl 13 without effecting gear train movement, that is to say, the lever 3 may be thrown from "off" to "on" position without effecting gear train movement, the pawl piece 13 ratcheting in the openings 76 of the main gear 19.

On the other hand, when the switch handle 3 is thrown from "on" to "off" position it is desirable, for reasons which will be stated, that the escapement be released so that the gear train may run down a predetermined amount. In order to accomplish this, there is provided a leg 39 (see Fig. 3) of said flexor 82 (Fig. 7) which is adapted to be engaged by an extending portion 83 on the switch handle which depresses the flexor 82 to a position in which it is spaced from the staff 78. In this position no braking action is effected and the gear train is released for action. Under these conditions the escapement may vibrate and permit the gear train to run down. Thus the flexor acts to prevent the escapement from operating until the switch lever has been returned to rest at its "off" position. Otherwise the escapement would operate to permit running down of the time delay mechanism while the switch lever rested at the "on" position. Fig. 7 shows how the flexor is provided with an offset 39 reaching through an opening 95 (Fig. 7) in the plate 70 for reacting contact with the switch lever 3.

The ratchet 18 has ten thirty degree teeth and one sixty degree tooth. The gear 19 has 12 openings corresponding to twelve angular divisions, so that each time a single movement from "off" to "on" of the switch handle 3 is effected, there will be normally an

advance of thirty degrees of the ratchet and main spring pawl 13, the pawl during advance strokes moving its detents from one opening to the next successive opening in gear 19. The gear at this time does not move for the reasons given above.

The main spring pawl 13 is also provided with a lug 84, which as the switch handle 3 is moved to "on" position is retracted in a clockwise direction (Figs. 2 and 7) through a thirty degree arc for every "on" movement of the handle 3. If the handle is moved to "on" position once, then a thirty degree retraction is effected and if it is moved twice a sixty degree retraction is made and so on. The purpose of the lug 84 is to serve as a release for latching parts which, it was said above, would be described in connection with the holding of the switch hammer in its Fig. 3 position against the compressive action of the spring 45. This mechanism will now be described:

Said mechanism comprises a latch cam 9 pivoted at 85. This cam has an extension 86 (Figs. 2, 4 and 7) having a claw 87 which is adapted to hook in under the ear 72 when said ear, by actuation of the switch lever 3 to its "off" position, is thrown into its Fig. 2 position. A sloping face 88 on the claw 87 permits the ear 72 to thrust it aside against the reaction of a leaf spring 12.

A time lever spring 47 reaches from a lug 89 to one arm 90 of a bell crank lever 91 in connection with which is the time lever 8 extending to the outside of the switch. The reaction points of the time lever spring 47 are so arranged that when the time lever 8 is thrown to its extreme positions, "on" and "off", there is an over-centering action, one way or the other.

There is provided on the bell crank 91 a second extension 101 adapted to engage with an extension lug 103 located on said latch cam 9. This cooperation takes place against the action of said spring 12. At the time when the bell crank lever 91 is in its Fig. 7 position, that is, in its "off" position, that the latch cam 9 is prevented from cooperating with the lug or ear 72.

When the time lever 8 is in its "on" position (Fig. 2) the latch cam 9 is ready to lock the ear 72 back, whenever the switch lever 3 is thrown into "on" position to throw the hammer 4 to the right as shown in Fig. 3. Whenever the time lever is in its "off" position there will be no latching (locking) action by the latch cam, and throwing of the switch lever 3 from "on" to "off" position results in immediately breaking the circuit instead of a delayed breaking being effected. It will be noted that the bell crank lever 91 for the time lever 8 is rotatably mounted on the hub member 30 (see Fig. 9). There is an advantage in having the spring 47 perform the over-centering and full stroking action

on lever 8 and in having the spring 12 perform the distinct action of pressing the latch cam into holding engagement. In a prior form of this switch I have caused a spring, corresponding to spring 47, to perform both of these functions. The advantage in the present method lies in the fact that the spring 12 may be made as light as is required for perfect action by the lug 72, and the spring 47 may be made as heavy as desired without effecting the unlatching action of lug 72. A reasonably heavy spring 47 is desirable in order that a definite over-centering action may be had in connection with the time lever 8.

A feature of the sloping face 88 of the latch cam 9 is that it is adapted to be engaged by the ear 84 or the main spring pawl 13 as said pawl returns under action of the main spring 44 used in driving the gear train, said train being controlled by the escapement. It will be noted that all increments of time added by throwing the switch lever 3 are equal, that is, subsequently to the first switch lever throw. That is to say, the pawl 13 moves through equal distances from its retracted position, and opening action of the switch (as the timing train runs down) is delayed proportionally to the time that it takes the pawl 13 to reach the latch cam 9. However, the interval caused by the first throw of switch lever 3 is that one in which the pawl 13 is immediately approaching the sloping face 88 of the latch cam 9. Inasmuch as this face slopes outwardly to the pawl 13 the last interval of time is shortened, because the latch cam 9 will release the ear 72 before the pawl 13 is moved through the full thirty degree arc. The advantage of this is that if it is desired to throw the switch to "off" position and merely walk out of the room or the like, the first delayed action will be relatively short. If it is desired to set the switch for a longer time such as until a reader falls asleep or the like, then the switch lever 3 may be operated two or more times and a proportionately longer time delay will be effected.

In Figs. 7 and 10, it will be noted, that one of the teeth of the ratchet subtends twice the amount of arc that the others do. The reason for this is that if the switch handle 3 is operated eleven times to set the switch for maximum time delay, it is undesirable that an operator be permitted to continue abnormally winding up the device by operating the switch handle 3. The long tooth Y prevents this, because the actuating stroke of the lug 74 is not great enough to catch back on the next tooth. Thus, the device is fool-proof.

The operation is as follows:

Assuming that the switch lever 3 and the time lever 8 are both in "off" positions, an operator may then throw the switch lever 3 to an "on" position and effect an instantaneous closure of the switch or to an "off" po-

sition again, with immediate and instantaneous operation, that is, it operates not unlike the ordinary toggle switch. The reason for this is that when the time lever 8 is in "off" position (to the right Fig. 7), then the time lever spring 47 is over centered so that the latch cam 9 is engaged by the lug 101 and is moved counter-clockwise and does not latch the ear 72. Even under this mode of operation, however, the present switch has novelty, in that the lost-motion engagement between the hammer 4 and the oscillating contactor 24 results in an exceedingly quick making and breaking of the circuit. The introduction of a pivoted or rocking type of contactor is advantageous over the sliding type in that wear is reduced and ease of operation enhanced.

Whenever it is desirable to operate the switch with the time-delay feature, it is only necessary to throw the time lever 8 to its "on" position (see Figs. 1 and 2). This results in the time lever spring 47 being over centered so as to cause the latch cam 9 to be forced clockwise by the spring 12, so that upon subsequently throwing the switch lever 3 to an "off" position the ear 72 will spring behind the claw 87 and be caught and so that upon subsequently turning the switch lever 3 to an "on" position the ear 72 will be held and hence the hammer 4 will also be held. Subsequently upon throwing of the switch handle 3 to an "off" position the toggle linkage shown in Fig. 3 will be held in circuit closing position until the gear train runs down under action of the main spring 44 and the control of the escapement mechanism. It will be appreciated that the movement of the switch handle 3 to "on" position resulted in the lug 74 moving the ratchet up one step and that at the same time the gear train was locked by the interfering action of the released flexor 82 on the escapement staff, said flexor having been released to permit interference by moving the switch handle 3 part 83 to "on" position. The return of the switch handle 3 to "off" position removes the interference of the flexor 82 from the escapement mechanism and permits the gear train to run down and the pawl 13 to return so as to effect movement of the latch cam 9 to release the ear 72, whereupon the overcentered compressed spring 45 snaps to move the contactor 24 and open the circuit.

As above described, for one cyclic movement of the switch handle 3 from "off" to "on" to "off" positions results in a comparatively short time delay, because of the advanced contact with the pawl 13 effected by the sloping surface 88 of the cam 9. It will be noted that when the switch lever 3 is thrown on, that the main spring pawl member 13 rides over the then locked main gear 19 (gear 19 is in the then locked train) and the detents 77 catch in the next set of openings of the main gear for subsequent return

therewith. The ratchet wheel 18 can return because when the switch lever 3 is in "off" position the lug 74 had ridden up the face of said opening 71 so as to clear the ratchet teeth.

If greater optimum time delay is desired, the operator after having set the time lever 8 to "on" position strokes the switch lever 3 to "on" position enough times to provide the total amount of time delay desired. For instance, the first stroke may provide a time delay of only one-half minute or so, due to the action of the face 88. Thereafter each stroke cumulatively adds time delay in proportion to the number of strokes effected. For instance, five minutes may be added per stroke, if each ratchet tooth provides arc enough that it takes the pawl five minutes to traverse the same with the particular escapement and gear train used.

One of the features of this cumulative action is that after the switch has once been turned on, subsequent stroking of the switch lever 3 does not result in the circuit being reopened, because it is locked shut (Figs. 2 and 3) by the latch cam 9 on the first stroke. The circuit is ready to spring open under action of the desired toggle linkage, whenever the switch handle 3 is turned off and the flexor 12 is released to permit running down of the escapement and gear train. The lug 84 then returns to effect opening of the switch at a predetermined time by throwing aside the latch cam 9.

Whenever it is desired to temporarily return to non-delay action this may be done by setting the time lever 8 to "off" position, before, after or during operation of the handle 3.

For the convenience of an operator, there is provided on the end of the shaft 30 which is fixed to the ratchet, a time indicator wheel 35 which may be viewed at its periphery through the opening 58 of the cover 10, referred to in connection with Fig. 1. The periphery of this indicator wheel is provided with suitable indicia representing the time that it will take for the switch to run down to an "off" position. Clearly, the indicia advance into registry with the opening 58 as the ratchet is advanced under the manipulation of the switch lever 3 to "on" and "off" positions. As the gear train runs down prior to automatically turning the switch off the time indicator wheel returns with it to zero indication. The last increment of scale reading near zero on the indicator is shorter than the others, because of the shorter increment of time consumed for traversing the spare effected by the first switch actuation, already described.

It is to be understood that the switch described is for application to circuits which are adapted to be turned "off" after a time delay. It is perfectly clear that the time may

be reversed so that the time delay action is effective to close the circuit after a predetermined time. This could readily be done by making the contactor move into circuit closing position after the time delay action, instead of into circuit opening position as it does now.

An advantage of this system over previous ones is that the timing mechanism does not operate the switch per se, but merely controls it according to mechanical relay principles. The timing mechanism has very little strain on it because of the gear reduction from the escapement to the main gear. The light frictional action of the spring 82 on the staff 78 is enough to lock the gear train against the frictional action between the pawl 13 and gear wheel 19. This is true because of the mechanical advantage existing between the staff on one hand and the said wheel 19 on the other hand, this advantage being effected by the described gear train. By separating the actions of springs 47 and 12, the releasing function on the latch cam 9 is rendered more sensitive without making the action of the time lever 82 too sensitive. The escapement mechanism cannot dead center, because there is always a tooth ready on the wheel 20—B for effecting a driving action on the escapement; or if a tooth has just escaped from the slot of the escapement and the next tooth has been blocked by contact with the surface of the escapement staff then dead centering cannot occur because the balance spring is flexed and ready to drive the staff back to permit passage of another gear tooth. It will be noted that the switch is free of any escapement pallets or like weak or intricate members.

Another advantage is that the timing mechanism can be made small and does not add much volume to the switch. This is because it does not operate the switch but merely controls it. The main spring 44 which stores energy from the manual operation of the operator does not receive its energy through the timing gears.

Another advantage is that the electrical elements per se are in a separate and isolated chamber and that the escapement mechanism is in another chamber, all elements being enclosed in porcelain. Hence the switch is fire-proof.

It is to be understood that the timing mechanism need not be wound up from time to time because, at the time of manufacture, initial tension is put into the main spring and actuation of the switch lever merely winds it up tighter after which it again runs down when delayed action is effected. The spring runs down to its initial tension condition.

It will be seen that if an operator should have the time lever in "on" position and serially operate the switch lever that he could

leave said switch lever in the "on" position and the lights or the like controlled from said position would continue burning without the time delay period being reduced, unless the switch handle were turned "off". When the switch handle is turned "off" the time delay periods start to become reduced as the gear train runs down to approach a point where the pawl 13 will trip out the latch cam 9, thus permitting the toggle circuit opening.

It will be clear that if an operator should set the switch for an extended delayed action and change his mind and desire to open the circuit immediately, this could readily be done by moving the time lever to "off" position. This (see Fig. 2) results in tripping the latch cam 9 and freeing the lug 72 so that upon setting the switch lever 3 to open position, if it is not already in such position, the switch will immediately open. If the switch lever is in "off" position when the time lever 8 is moved to "off" position the switch immediately breaks the circuit.

Opening of the circuit by setting the time lever to "off" position while the switch lever is in "off" position does not affect the operation of the timing train. Hence, if the time delay had been set for one-half hour and then the switch immediately opened by setting both time and switch levers to "off" positions, the timing train would have continued to run while the circuit was open (for instance, after the lights were out); then, if fifteen minutes later the switch were again turned on by means of the switch lever there would still remain fifteen minutes of time delay action available. However, an operator would be aware of this because the indicator 35 would show it.

It will be noted that after the time lever 8 has been snapped to "off" position, thereby eliminating the time delay operation, still the switch lever 3 operates the time movement, thus preventing the movement from becoming "frozen" or gummed with oil, dust and lint or the like, and causing it more likely to remain in operable condition.

Likewise, should the gear train "freeze" with foreign material, an operation of lever 3 would build up force in the main spring 44 to eventually force the "freeze." It will further be noted that upon operation of the switch once per day, the operator would, unconsciously, add force which in the end would probably break the "freeze", so that the operator finding the switch apparently out of order might find it back in order after a few reciprocations of lever 3.

In view of the above, it will be seen that the several objects of the invention are achieved and other adantageous results attained.

As many changes could be made in carrying out the above constructions without departing from the scope of the invention, it is

intended that all matter contained in the above description or shown in the accompanying drawings shall be interpreted as illustrative and not in a limiting sense.

I claim:

5. 1. In a switch, a switch handle, means for effecting delayed action by said switch handle, including an escapement, a staff included in said escapement, a resilient braking member engaging and normally preventing operation of said staff, said resilient braking member being engaged by said switch handle to release the staff for escapement operation when said switch handle is in circuit opening position.
10. 2. In a time delay switch circuit making and breaking means, a switch lever for operating said means, a latch for temporarily holding the circuit making and breaking means in a predetermined position, a latch releasing means adapted to be retracted from the latch a distance which is a function of the number of times the switch lever is operated, a timing mechanism adapted to return the latch releasing means to move the latch whereby the latter releases the switching means, a timing lever, means associated with the timing lever for rendering the latch ineffective at one position of the lever but effective at another, an over-centering spring reacting to effect full-stroke of the timing lever and a separate spring reacting against the latch to normally set it in holding position, said last-named spring operating independently of said first-named spring.
15. 3. In a switch, timing means, a latch operative with said timing means, a timing lever adapted to set said latch in a non-holding position when the lever is at one extreme and in a holding position when the lever is at its other extreme, an over-centering spring adapted to force the lever completely to one position or another and a separate spring normally pressing the latch into engagement with at least one element of said timing means.
20. 4. In a switch, timing means, a latch operative with said timing means, a timing lever adapted to set said latch in a non-holding position when the lever is at one extreme and in a holding position when the lever is at its other extreme, means adapted to hold the lever completely at one position or another, and separate means normally pressing the latch into engagement with at least one element of said timing means.

In testimony whereof, I have signed my name to this specification this 14th day of November, 1929.

MARCUS H. RHODES.
